(57) **CLAIM**

The ornamental design for an artificial lash extension, as shown and described.

DESCRIPTION

FIG. 1 is a top right perspective view of an artificial lash extension in accordance with the claimed design, shown in the first embodiment;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top right perspective view of an artificial lash extension shown in a second embodiment;

FIG. 9 is a front view of thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a top right perspective view of an artificial lash extension shown in a third embodiment;

FIG. 16 is a front view of thereof;

FIG. 17 is a rear view thereof;

FIG. 18 is a right side view thereof;

FIG. 19 is a left side view thereof;

FIG. 20 is a top view thereof; and,

FIG. 21 is a bottom view thereof.

The broken lines consisting of evenly space lines in the figures show portions of the artificial lash extension that form no part of the claimed design. The broken lines consisting of dash dot lines in the figures show break lines that form no part of the claimed design. The artificial lash extension is shown with symbolic breaks in its length. The appearance of any portion of the article between the break lines forms no part of the claimed design.

1 Claim, 21 Drawing Sheets
